(57) **CLAIM**

The ornamental design for a water craft, as shown and described.

DESCRIPTION

FIG. 1 is a perspective view of a water craft taken generally from a top and rear side thereof;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines and the region enclosed by the broken lines (FIGS. 2 and 7) that generally form a central bottom portion of the water craft depict subject matter that forms no part of the claimed water craft design and are included for the purpose of illustrating the full water craft.
